MECHANICAL MOVEMENT

John Gordon Baker, Evansville, Wis., assignor to
 Baker Manufacturing Company, Evansville,
 Wis., a corporation of Wisconsin

Application March 6, 1941, Serial No. 382,005

8 Claims.

(Cl. 74—44)

This invention relates to mechanisms for converting rotary motion into reciprocatory motion and more particularly to such mechanism wherein the reciprocating part is guided for rectilinear movement and the conversion is effected by a crank.

One object is to provide a mechanism of the above character in which the lines of action of the actuating and reactionary forces are located in a novel manner relative to the guide so as to minimize the bending stresses imposed on the latter.

Another object is to guide the reciprocating part in a novel manner.

Other objects and advantages of the invention will become apparent from the following detailed description taken in connection with the accompanying drawings, in which

Figure 1 is a vertical sectional view through a power driven actuating mechanism involving the novel features of the present invention, the section being taken along the line 1—1 of Fig. 2.

Fig. 2 is a section taken along the line 2—2 of Fig. 1.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

In the drawings, the invention is shown for purposes of illustration as a mechanism for converting rotary power derived, for example, from an electric motor 5 into reciprocatory motion and applying such motion to a driven member in the form of a rod 6 connected to a pump or other device to be reciprocated. The main operating parts are supported by a hollow casting 7 cooperating with a cover 8 to form a housing. The pump rod may, if desired, be housed in an auxiliary cover 9. Herein, the motor is supported externally of the housing on a bracket 10 and a pulley 11 on its shaft carries belts 12 driving a pulley 13 on the outer end of a shaft 14. The latter projects into the casing 7 and is journaled in bearings carried by opposite side walls 7^a and 7^b of the latter.

The pump rod 6 is suspended at its upper end from a vertically movable arm or slide 15 disposed within the housing with its free end projecting through an opening 16 in the cover 8 and

clamped between nuts 17 on the rod. The rod is located as close as possible to the casing wall 7^b. As shown, the slide 15 comprises an irregularly shaped casting disposed horizontally within the housing and slideable along spaced guides 18 and 19 which extend parallel to the direction of reciprocation of the pump rod. Herein the guides take the form of vertical rods seated at their lower ends in bosses 20 and 21 upstanding from the bottom wall of the casing 7. Intermediate their ends, the rods are guided through lugs 22 and 23 cast integral with the walls of the casing 7 near the open end thereof. By virtue of their wide spacing and the support provided by the spaced bosses and lugs on the box-like casing, the guide surfaces are supported with extreme rigidity.

Holes are bored in opposite sides of the slide 15 to provide bearing surfaces 24 and 25 to receive the upper ends of the rods 18 and 19. To increase the effective length of the guides, the coating surfaces on the slide are divided into two parts disposed on opposite sides of the lug 22. For this purpose, a rigid arm 26 cast integral with the slide extends downwardly past the lug 22 and has a bored lower end portion 27 received on and slideable along the larger rod 18 between its supporting boss 20 and the lug 22. The spacing of the portion 27 and the bearing surface 24 is approximately equal to that of the boss 20 and the lug 22 as a result of which each pair of holes may be bored using a single tool set up. A substantial reduction in manufacturing cost is thus effected.

A crank mechanism is provided for converting the rotary motion of the shaft 14 into reciprocation of the slide 15. To this end, a pinion 28 is carried by the shaft 14 within the casing and meshes with teeth 29 around the periphery of a larger gear 30 which is disposed as close as possible to the casing wall 7^b and therefore to the pump rod 6. For this purpose, the gear hub 31 is journaled on a stud 32 projecting inwardly from the casing wall and preferably cast integral with this wall. A plate 32^a fastened to the stud by screws 33 holds the gear on the stud.

A pitman 34 which connects the crank gear 30 to the slide intermediate the ends of the latter is especially constructed to provide for optimum lateral compactness of the unit as a whole and minimum lateral spacing of the pump rod and line of action of the actuating force applied by the pitman. To these ends, the pitman is of generally U-shape with the closed end of the U projecting beyond the rod 18 toward the casing wall 7^a as shown in Fig. 2. A recess 35 in the

under side of the slide receives the upper end portion of the pitman and the laterally extending end 36 is journaled in a bearing 37 supported in a cross-rib 38 on the slide, the bearing recess being closed by a cap 39. The lower end 40 of the pitman constitutes the crank pin and is similarly constructed and mounted in a bearing 41 disposed in a hole 42 in the gear 30 and spaced from the gear axis to give the proper crank throw. The guide rod 19 is disposed closer to the casing wall 7^a than the rod 18 so as not to interfere with the rotation of the crank pin.

It will be observed that the line of action of the actuating force is in the plane of the crank gear and the bearings 37 and 41 and therefore is disposed close to the casing wall 7^b.

In the rotation of the crank gear, the slide 15 is alternately raised from the position shown and then lowered and the pump rod is moved correspondingly. This motion is utilized to actuate the piston 43 of a pump 44 and elevate oil from the reservoir formed by the casing through a tube 45 from which the oil is delivered to recesses 46 and 47 on the upper surface of the slide and thus distributed to the guide rod surfaces and through a hole 48 to the upper pitman bearing.

The arrangement of the crank in the manner above described between the guide surfaces and the actuated rod 6 enables the bending stresses exerted on the guides to be minimized. This is for the reason that with the lines of action of the oppositely directed actuating and reactionary forces disposed on the same side of the guides, the bending moment exerted on the guides is determined solely by the differences in lengths of the moment arms of the two forces and is independent of the spacing of the force lines from the guides. Thus, on the upstroke, the actuating force applied by the crank is directed upwardly and generally parallel to the guideways and in line with the pitman bearings. The reactionary force exerted by the pump is directed downwardly along the axis of the rod 6. During the downstroke, these directions are reversed. The moment arms of these forces are the respective distances of the bearing 37 and the rod 6 from the guide rods 18 and 19 and, being on the same side of the rods, the resultant bending moment applied by the slide to the guides is the difference in lengths of the two arms or the distance between the two force lines multiplied by the actuating force. This effective moment arm, and therefore the net bending stress, is reduced to a minimum in the present instance, the pitman and the pump rod being disposed as close together as possible.

I claim as my invention:

1. Mechanism of the character described having, in combination with a reciprocable member to be actuated, a hollow casing disposed adjacent said member, a stud rigid with and projecting inwardly from the wall of said casing adjacent said member, a power driven gear rotatable on said stud, a guide rod supported in said casing on the side of said gear opposite said member and providing a guideway extending parallel to the path of said member, a slide reciprocable along said rod and projecting laterally thereof beyond said gear, means connecting the projecting end of said slide to said member, and a U-shaped connecting rod with its closed end projecting past said rod and having ends extending laterally toward said gear with one end journaled in said gear eccentrically of the axis thereof and

the other being pivotally connected to said slide intermediate said rods and the connection with said member.

2. Mechanism of the character described having, in combination with a reciprocable member to be actuated, a frame plate disposed adjacent and extending substantially parallel to said member, a power driven gear disposed close to the other side of said plate and supported therefrom to turn on an axis extending transversely of said member, a guideway mounted in said casing and spaced from said gear on the side thereof opposite said member, said guideway extending parallel to the path of the member, a slide reciprocable along said rod and projecting laterally thereof beyond said gear, means connecting the projecting end of said slide to said member, and a connecting rod having one end journaled in said gear eccentrically of the axis thereof and the other being pivotally connected to said slide intermediate said rod and the connection with said member.

3. Mechanism of the character described having, in combination with a reciprocable member to be actuated, a power driven crank mounted adjacent said member for rotation in a plane parallel thereto, a pair of guide bars extending parallel to the path of said member and disposed in spaced relation to and on the side of said crank opposite said member, a slide reciprocable along said bars and projecting laterally thereof, means connecting the projecting end of said slide to said member, and a connecting rod disposed in the space between said bars and having one end pivotally connected to said crank and the other pivotally connected to said slide intermediate said bars and the connection with said member.

4. Mechanism of the character described having, in combination with a reciprocable member to be actuated, a hollow casing disposed adjacent said member, a power driven crank mounted in said casing to rotate in a plane parallel to said member, a guide supported in said casing and spaced laterally from the path of reciprocation of said member and on the side of said crank opposite said member, a slide reciprocable along said guide and projecting laterally thereof beyond said crank, means connecting the projecting end of said slide to said member, and a connecting rod having one end journaled in said crank and the other end pivotally connected to said slide intermediate said guide and the connection with said member.

5. Mechanism of the character described having, in combination, a frame plate, an actuated element disposed close to one side of said plate and reciprocable therewith, a power driven crank gear rotatably supported on said plate closely adjacent the side thereof opposite said element, a guide disposed adjacent said gear on the side thereof opposite said element and extending parallel to the path of said element in laterally spaced relation relative thereto, a slide projecting laterally from and reciprocable along said guide and connected at its free end to said element, and a pitman connecting said crank gear and said slide intermediate the ends of the latter.

6. Mechanism of the character described having, in combination, a slide, a guide supporting said slide for reciprocation, a power rotated crank disposed adjacent said guide and connected by a pitman to said slide for reciprocation of the latter back and forth along said guide, and an actuated element connected to said slide on

the side of said crank and pitman opposite said guide.

7. Mechanism of the character described having, in combination, a slide, a guide supporting said slide for reciprocation, a power rotated crank connected to said slide for reciprocation of the latter back and forth along said guide, and an actuated element connected to said slide and reciprocated thereby, said element and the crank connection thereto being laterally spaced relative to said guide to locate the lines of the force application by said crank and the force reaction by said element on the same side of said guide and laterally spaced therefrom.

8. Mechanism of the character described hav-

15

ing, in combination, a slide, a guide supporting said slide for reciprocation, a power reciprocated actuating element connected to said slide to move the latter back and forth along said guide, and an actuated element connected to said slide on the same side of said guide as said actuating element and reciprocated back and forth with the slide, said actuating and actuated elements being spaced from said guide on the same side of the latter and from each other whereby the actuating and reactionary bending moments exerted on said guide by these elements counteract each other.

JOHN GORDON BAKER.
